CONE FEEDING MECHANISM

William S. Whiting, Jr., Canton, N. C., assignor
to The Champion Fibre Company, Canton,
N. C., a corporation of Ohio

Application March 3, 1934, Serial No. 713,941

15 Claims. (Cl. 312—44)

The present invention relates to dispensing apparatus, and is concerned more particularly with the provision of a cone feeding mechanism whereby conically shaped receptacles or hollow articles may be delivered singly or individually to a point of use as desired.

While the invention finds its principal application as a means for feeding paper cones, such as are used in textile industries, to a finishing machine or the like, it is not restricted thereto but may be employed in other relations wherein it is desired individually to advance conically shaped hollow articles from a stack thereof to a point of use. The organization is adapted for automatic operation.

An object of the present invention is the provision of an apparatus of the above-mentioned class which shall function to hold the stack of cones while releasing the lowermost cone of the stack and positively disengaging the latter from said stack and feeding the same to a point of use.

The above, and other, objects of invention are attained by an organization to be described in detail in the following description taken in conjunction with the appended drawing which illustrates a preferred embodiment of the apparatus forming the basis of the present invention.

Referring to the drawing: Figure 1 is a fragmentary side elevation of a cone feeding mechanism embodying the invention. Figure 2 is a sectional view of the mechanism taken on line C—C of Figure 1, showing the relative position of the plurality of latch fingers and snatch springs employed. Figure 3 is a vertical section on line A—A of Figure 2, showing the position of the snatch springs with respect to a stack of cones; while Figure 4 is a section on line B—B of Figure 2, showing the position and mode of operation of the latch fingers. In the drawing, like reference characters refer to like parts throughout the several views.

Broadly considered, the apparatus forming the basis of the present invention comprises a suitable chute for receiving nested cones, combined means for normally maintaining a nest of cones in one position with respect to the chute and for freeing the lowermost cone from the nest and delivering the so-freed cone, by gravity, to a point of use while maintaining the remaining cones of the nest in the normal position in the chute, and means for imparting operative movement to said combined means. In this assembly, the combined means may and preferably does include a latch means at least one portion of which extends through the wall of the chute and into engaging

relation with at least the lowermost cone of the nest, said latch means, preferably an oscillatable latch pivoted to the chute, having on that portion of it which extends into the interior of the chute a lug having a shoulder, said portion being characterized more specifically in that it includes a detent surface, the aforesaid lug, and a second detent surface constituting the shoulder surface of said lug.

The above-described latch means functions as follows: when the same is in "normal" (i. e., non-oscillated) position its first-mentioned detent surface engages and supports the lowermost of the nest of cones and hence the whole nest. As the latch means is oscillated its lug engages the upper edge of the lowermost cone, exerting a downward pressure thereon. At the same time, the oscillation brings the shoulder surface of said lug into supporting engagement with the next to the lowermost cone.

The aforesaid latch means may be, and preferably is, pivotally attached to the exterior of said chute, there being provided in one portion of the latter at least one aperture through which the cone-engaging portion of the latch means extends.

For insuring positive release of the lowermost cone from the nest thereof and delivery of the same, by gravity, to a point of use, I may, and preferably do, provide on said operative movement-imparting means a snatch spring adapted to contact with the upper edge of the lowermost cone and to impart to the latter a positive downward pull. Where the said movement-imparting means is located outside said chute, I provide an aperture in the wall of the latter through which a portion of said snatch spring extends in contacting relationship to the lowermost cone of the nest.

A specific apparatus embodying my invention preferably comprises, in combination, a suitable housing 1 as the chute for the stack of cones to be disposed therein in substantially vertically nested arrangement and with their mouths upward, said housing providing therein an upper stack-retaining zone *a*, an intermediate cone-dispensing zone *b* and a lower cone-feeding or delivering zone *c*, and being apertured in its intermediate zone as at 2, 2, a cam collar 3 as the operative movement-imparting means about the housing at said intermediate zone, said collar being vertically reciprocatable with respect to said housing and being provided with a beveled surface 4 at its top edge, means 5, 5 for vertically reciprocating said collar, a plurality of latch fingers 6, 6, pivotally mounted on the housing 1

as at 7, 7, and a plurality of snatch springs 8, 8, mounted on said cam collar 3.

- The housing 1 may be, and preferably is, a cylindrical conduit of a diameter to freely confine a stack of cones; it may have any desired and suitable longitudinal dimension in its upper zone *a* and in its lower zone *c*, and may be curved (as is indicated in the drawing in zone *c*) to accommodate the apparatus to the whole organization of which it may be a part. As shown in the drawing it is pierced in its intermediate zone *b* by eight vertical slots or apertures diametrically in pairs, said slots to accommodate four snatch springs 8, 8, and four latch fingers 6, 6. 10 The snatch springs 8, 8, are mounted upon cam collar 3 in spaced relation by means of cap screws 8', 8'. These springs extend substantially vertically from the cam collar 3 for a convenient distance, their upper portions being inwardly inclined for entrance through diametrically opposed slots 2, 2, into the interior of housing 1 and terminating in hooked ends 9, 9. The curvature of the upper portions of snatch spring 8, 8, is such, and their hooked ends 9, 9, are of such 20 relative shape and size, that they may be advanced or slid over the outer surface of a cone and over the upper edge thereof by upward movement of cam collar 3 but will insure that said hooked ends 9, 9, positively engage the upper edge of such cone and exert a downward pull thereon when the cam collar 3 is moved downwardly.

The latch fingers 6, 6, (here shown as being four in number) which are pivotally mounted at 35 their upper ends as by pivots 7, 7, in diametrically opposed slots 2, 2, of housing 1 in spaced relation, present inner surfaces which in their lowermost portions are substantially plane and which, in the normal position of the latch fingers, are substantially parallel with but spaced from 40 the outer wall of housing 1, but which are inwardly curved as at 10, 10, intermediate the ends of said elements to cooperate with and receive actuation from cam collar 3. At their upper ends 45 they terminate in beveled surfaces 11, 11, constituting detent surfaces. At the outer and upper ends of said beveled surfaces 11, 11, are lugs 12, 12, whose shoulder surfaces 13, 13, are substantially plane and constitute further detent surfaces. The bevel of surfaces 11, 11, is such 50 that when the latch fingers 6, 6, are in substantially vertical (i. e., normal) position, surfaces 11, 11, contact with and engage the upper portion of the lowermost cone of the stack thereof. 55 The bevel of lug surfaces 13, 13, is such that said surfaces may contact and engage the next to the lowermost cone of the stack when latch fingers 6, 6, are moved to the 6', 6', position by cam collar 3.

- 60 Cam collar 3 is vertically reciprocated, through pivoted links 5, 5, being actuated from any suitable reciprocating means (not shown) timed as to motion to accommodate a desired operation of the entire organization of which the present apparatus may be a part. The curvature of the 65 curved surface 4 at the upper end of cam collar 3 is such that the said cam collar, in its upward movement, can oscillate the latch fingers 6, 6, moving the same from their normally substantially vertical position outwardly to the position indicated at 6', 6', by engagement with the curved inner surfaces 10, 10, of said latch fingers, thus moving the upper ends of the pivoted latch fingers inwardly and downwardly whereby to cause the 70 lugs 12, 12 to engage the upper edge of the lower-

most cone of the stack in housing 1 and to exert a downward pressure thereon while simultaneously moved detent surfaces 11, 11, out of engagement with the lowermost cone and presenting shoulder surfaces 13, 13, for engagement with the next higher cone of the stack whereby to retain the same, and hence the stack of cones, in the intermediate zone *b* of said housing. 5

In operation, a stack of nested cones is placed in the upper zone *a* of housing 1, the lowermost cone resting on surfaces 11, 11, of latch fingers 6, 6, and pivoted links 5, 5, are caused to move the cam collar 3 upwardly and downwardly over a portion of intermediate zone *b* of housing 1. 10 With each upward movement of the cam collar 15 the latch fingers 6, 6, are moved to position 6', 6', thereby releasing the lowermost cone of the stack, engaging the upper position of the next lowermost cone and exerting a downward pressure on the upper edge of the lowermost cone; simultaneously the upward movement of cam collar 3 slides the hooked ends 9, 9, of snatch springs 8, 8, 20 upwardly over the upper edge of the lowermost cone where, by virtue of the inclination of said springs, the said hooked ends engage the upper 25 edge of said lowermost cone. With downward movement of cam collar 3 the snatch springs 8, 8, exert a downward pull upon the engaged edge of the lowermost cone, moving the same downwardly out of intermediate zone *b* and into the 30 delivering zone *c* through which it may descend by gravity: simultaneously, as cam collar 3 is downwardly moved over curved surfaces 10, 10 of latch fingers 6, 6, the latter are allowed to return to their so-called normal position, thereby disengaging shoulder surfaces 13, 13 from supporting contact with the now lowermost cone of the 35 stack and engaging the detent surfaces 11, 11 with the said cone whereby to hold the same, and hence the stack of cones, from moving out 40 of intermediate zone *b*.

Where the lower portions of pivoted latch fingers 6, 6 are not sufficiently heavy to insure the return of said latch fingers to substantially vertical position upon descent of cam collar 3, 45 or where for any other reason the same is desired, suitable springs, as shown at 14, 14, may be employed for the purpose of maintaining continuous contact between said latch fingers and said cam collar. 50

It will be appreciated that the relative dimensions, and shapes, of the cooperating elements of this device will be determined at least in part by the size and type of cones to be handled thereby, and that a greater or lesser 55 number of latch fingers and/or of snatch springs may be employed, depending likewise upon the size and type of articles to be dispensed.

I claim:

1. In a cone feeding mechanism, a chute for 60 receiving nested cones and through which same are adapted to be individually fed to a point of discharge; combined integral holding and releasing means formed with an inclined detent surface adapted to engage the side of a cone for 65 normally maintaining a nest of cones in one position with respect to said chute, said means having a lug formed above said detent surface for freeing the lowermost cone from said nest and an inclined shoulder above said lug adapted 70 to engage the side of a superposed cone for retaining the remainder of said nest meanwhile in said normal position; and means for imparting operative movement to said combined means.
2. In a cone feeding mechanism, a chute for 75

receiving nested cones and through which same are adapted to be individually fed to a point of discharge; combined integral holding and releasing means formed with an inclined detent 5 surface adapted to engage the side of a cone for normally maintaining a nest of cones in one position with respect to said chute, said means having a lug formed above said detent surface for freeing the lowermost cone from said nest 10 and an inclined shoulder above said lug adapted to engage the side of a superposed cone for retaining the remainder of said nest meanwhile in said normal position; and means reciprocatably mounted on said chute for imparting operative movement to said combined means.

3. In a cone feeding mechanism, a chute for receiving nested cones and through which same are adapted to be individually fed to a point of discharge, combined integral holding and releasing means having an inclined detent surface for normally maintaining a nest of cones in one position with respect to said chute and including a lug for freeing the lowermost cone from said nest and having a shoulder for retaining 20 the remainder of said nest meanwhile in said normal position, means reciprocatably mounted on said chute for imparting operative movement to said combined means, said movement-imparting means including a snatch spring adapted 25 to contact the lowermost of said nest of cones and to impart to said lowermost cone a downward movement.

4. A mechanism for individually feeding cones from a gravity-influenced nest of cones comprising, in combination, a cylindrical housing adapted to enclose a nest of cones and being longitudinally apertured at one portion thereof, a cam means reciprocatably mounted on said housing adjacent said apertured portion, means 30 for reciprocating said cam means, an integral latch means cooperatively mounted with respect to the longitudinally apertured portion of said housing and capable of oscillatory movement with respect thereto, said latch means having a portion extending within said housing by reason of the latter's apertured formation, said portion having vertically spaced inclined detent surfaces adapted for engagement alternately with said nest of cones and provided also with portions 35 operated upon by said cam means, said latch means operable in response to reciprocation of said cam means to free the lowermost cone of said nest and to hold the remainder of said nest against movement longitudinally of said housing, and means carried by said cam means for moving said freed cone longitudinally of said housing.

5. A mechanism for individually feeding cones from a gravity-influenced nest of cones comprising, in combination, a cylindrical housing adapted to enclose a nest of cones and being longitudinally apertured at one portion thereof, a cam means reciprocatably mounted without said housing and adjacent said apertured portion, means for reciprocating said cam means, an integral latch means cooperatively mounted with respect to the longitudinally apertured portion of said housing and capable of oscillatory movement with respect thereto, said latch means having portions extending within said housing by reason of the latter's apertured formation for engagement with said nest of cones and provided also with portions operated upon by said cam means, said latch means operable in response to reciprocation of said cam means to free the lowermost cone of said nest and to hold the remainder of said nest against movement longitudinally of said housing, and means carried by said cam means for moving said freed cone longitudinally of said housing.

6. A mechanism for individually feeding cones from a gravity-influenced nest of cones comprising, in combination, a cylindrical housing adapted to enclose a nest of cones and being longitudinally apertured at one portion thereof, a cam means reciprocatably mounted without said housing and adjacent said apertured portion, means for reciprocating said cam means, an integral latch means cooperatively mounted with respect to the longitudinally apertured portion of said housing and capable of oscillatory movement with respect thereto, said latch means having portions extending within said housing by reason of the latter's apertured formation for engagement with said nest of cones and provided also with portions operated upon by said cam means, said latch means operable in response to reciprocation of said cam means to free the lowermost cone of said nest and to hold the remainder of said nest against movement longitudinally of said housing, and means carried by said cam means for moving said freed cone longitudinally of said housing.

7. Mechanism as defined in claim 4, in which the cone-moving means carried by said cam means includes a spring.

8. Mechanism as defined in claim 4, in which the cam means includes a collar surrounding said housing.

9. Mechanism as defined in claim 4, in which a plurality of the said latch means are employed.

10. Mechanism as defined in claim 4, in which said cam means carries a plurality of said cone-moving means.

11. Mechanism as defined in claim 4, in which the said latch means is maintained in contact with said cam means by means of a spring.

12. A mechanism for individually feeding cones from a gravity-influenced nest of cones comprising, in combination, a cylindrical housing adapted to enclose a nest of cones and being longitudinally apertured at one portion thereof, a cam collar reciprocatably mounted without said housing and adjacent said apertured portion, means for reciprocating said cam collar, a latch finger cooperatively mounted with respect to the longitudinally apertured portion of said housing and capable of oscillatory movement with respect thereto, said latch finger having vertically spaced inclined portions extending within said housing by reason of the latter's apertured formation for alternate engagement with said nest of cones and provided also with portions operated upon by said cam collar, said latch finger being operable in response to reciprocation of said cam collar to free the lowermost cone of said nest and to hold the remainder of said nest against movement longitudinally of said housing, and snatch springs carried by said cam collar and having a portion which extends within said housing by virtue of the latter's apertured formation for moving said freed cone longitudinally of said housing.

13. A mechanism for individually feeding cones from a gravity-influenced nest of cones comprising, in combination, a cylindrical housing adapted to enclose a nest of cones and being longitudinally apertured at one portion thereof, a cam collar reciprocatably mounted without said housing and adjacent said apertured portion, means for reciprocating said cam collar, a latch finger cooperatively mounted with respect to the longitudinally apertured portion of said housing and capable of oscillatory movement with respect thereto, said latch finger having portions extending within said housing by reason of the latter's apertured formation for engagement with said nest of cones and provided also with portions operated upon by said cam collar, said latch finger being operable in response to reciprocation of said cam collar to free the lowermost cone of said nest and to hold the remainder of said nest against movement longitudinally of said housing, and snatch springs carried by said cam collar and having a portion which extends within said housing by virtue of the latter's apertured formation for moving said freed cone longitudinally of said housing.

- 5 longitudinally of said housing, the portion of said oscillatory latch finger which extends within said housing including an inclined detent surface adapted to supportably engage the side of a cone and a lug thereabove, said lug being provided with a second inclined detent surface likewise adapted to support a superposed cone of said nest when brought into engagement therewith by oscillation of said latch finger.
- 10 14. A mechanism for feeding textile cones from a gravity influenced nest thereof comprising a cylindrical casing for receiving said nest of cones, said casing having a plurality of circumferentially spaced elongated apertures formed therein, a plurality of latch members pivotally mounted in circumferentially spaced relation on said casing, each of said latch members comprising a one piece body having a portion projecting through one of said elongated apertures into
- 15 said casing, said projecting portion providing vertically spaced inclined detent surfaces adapted for alternate engagement with a stack of cones in said casing, said latch members having a depending leg portion outside of said casing and
- 20 embodying an inwardly directed cam surface, a
- 25

sliding cam collar surrounding said casing and adapted for engagement with the cam surfaces of said latch members to impart pivotal motion thereto to disengage the lower detent surface from the lowermost cone of said stack and to engage the upper detent surface with the next lowermost cone of said stack.

15. Mechanism for feeding textile cones from a gravity influenced nest thereof including a casing for receiving said nest of cones, a latch member pivotally mounted on said casing for rocking movement in a vertical plane, said latch member comprising a one piece body providing vertically spaced inclined detent surfaces adapted for alternate engagement with the side face of each cone of a stack thereof in said casing, said latch member having a depending leg portion embodying a cam surface, and reciprocable means adapted for engagement with said cam surface to impart pivotal motion to said latch member to disengage the lower detent surface from the lowermost cone of said stack and to engage the upper detent surface with the next lowermost cone of said stack.

WILLIAM S. WHITING, JR. 25
